UNITED STATES PATENT OFFICE

2,619,818

METHOD OF MAKING AN ELASTIC WELT
FOR FULL FASHIONED STOCKINGS

Paul R. Nestler, Green Lane, Pa.

Application April 26, 1949, Serial No. 89,655

1 Claim. (Cl. 66—173)

1

My invention relates to an elastic welt for full fashioned stockings and a method of making the same.

One object of the invention is to produce an improved elastic welt and an improved method of making the same.

A further object is to produce an elastic welt without the use of rubber bands or strands.

A still further object is to produce an elastic welt which is easily made by merely adjusting or controlling the action or operation of the usual full fashioned knitting machines.

These and other objects are attained by my invention as set forth in the following specification and as illustrated in the accompanying drawings in which:

Fig. 1 is a diagrammatic plan view of a stocking welt illustrating one embodiment of the invention.

Fig. 2 is similar to Fig. 1, but showing another embodiment of the invention.

Fig. 3 is a diagrammatic view showing the manner in which the welt of Fig. 1 or of Fig. 2 is made.

Fig. 4 is a diagrammatic, vertical sectional view of the upper portion of a stocking, showing the completed welt.

In carrying out the invention, I first knit a few courses 10 of ordinary loop stitches which, in the finished stocking, constitute the lower edge 12 of the inner wall 14 of the welt. When a sufficient number of courses 10 have been knit, stitches 16, in suitably spaced wales, are transferred, to the right or to the left, and are locked on adjacent needles.

Beyond the locked stitches 16, I form a large number of courses 18 of ordinary loop stitches, and during the knitting of these courses, the stitches on the needles from which stitches 16 were transferred are dropped to form ladders 38 which extend from the locked stitches to the vicinity of the other edge of the welt wall 14. It will be noted that the band formed by courses 18 (Fig. 3) is relatively narrow and that the portion formed of courses 18 and ladders 38 is relatively long whereby the ladders extend over the major portion of the inner wall 14 of the welt. At the end of the ladders 38 I knit another relatively narrow band formed of courses 20 of ordinary loops, and at the end of this narrow band I knit one or more courses of picot, or other open work locked stitch which forms a fold line between the inner and outer walls of the welt.

If it is desired to produce the embodiment shown in Fig. 1, the outer wall 24 of the entire welt is knit of ordinary loop stitches such as the loops forming the courses 18 or 20, and, when the outer wall 24 is of the desired length, or when it extends from the open stitches 22 to about the line 26, the welt is transferred from the welt bar onto the legger and the leg 28 is knit in any desired manner.

If it is desired to produce the embodiment of Fig. 2, the pattern of the inner welt wall 14 is repeated in the knitting of the outer wall 24 of the

2

welt. This is done by knitting courses 30, corresponding to the courses 20, locking selected stitches 32, corresponding to the locked stitches 16, knitting courses 34 corresponding to courses 18 and, finally, knitting courses 36 corresponding to courses 10.

The formation of the ladders 38 imparts to the welt a certain amount of elasticity in both the transverse and longitudinal directions. While, as shown in the drawings, the ladders are formed in every seventh or eighth wale, it is to be understood that the spacing of the ladders can be varied according to the degree of elasticity desired. It will be noted that, in both embodiments, the ladders stop short of the fold line 22, which in the finished stocking constitutes the upper edge of the welt, so that the garters may be engaged with the solid knit upper marginal portions of the welt.

By the invention disclosed no rubber bands or strands are used and the stitches are not enlarged, slackened or loosely formed so that the appearance of the welt is not marred. In fact, the presence of the ladders causes the welt to contract somewhat, when not positively distended, so that the welt will tend to fit, or accommodate itself to, a smaller leg, while, at the same time it is capable of stretching so as to accommodate itself to a thicker leg.

What I claim is:

The method of knitting a stretchable welt for a full fashioned stocking, which method includes knitting a relatively small number of courses of plain loop stitches to form a relatively narrow upper marginal portion, transferring stitches from selected wales onto needles in adjacent wales to form locked stitches in said adjacent wales, knitting a relatively larger number of courses to form the main body portion of a wall of the welt, dropping the stitches from the needles which correspond to the locked stitches to produce ladders extending from the bottom edge of said upper marginal portion to the bottom edge of said main body portion, and knitting a relatively small number of courses of plain stitches to produce a lower marginal portion between the main body portion and the top of the stocking leg.

PAUL R. NESTLER.
